COMBINATION TRASH AND SMOKER'S RECEPTACLE

Barbara Ellen Boykin, 106 Oakland Ave.,
Manning, S.C. 29102

Filed Oct. 24, 1969, Ser. No. 19,710

Term of patent 14 years

Int. Cl. D27—03

U.S. Cl. D85—2

The single figure is a view of a combination trash and smoker's receptacle embodying my new design.

I claim:

The ornamental design for a combination trash and smoker's receptacle, as shown.
